CLAIM

The ornamental design for a balance vehicle as shown and described.

DESCRIPTION

FIG. 1 is a rear, left, and top perspective view of a first embodiment of a balance vehicle showing my new design; FIG. 2 is a front, left, and top perspective view of FIG. 1; FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top view of FIG. 1; and,

FIG. 8 is a bottom view of FIG. 1.

The broken lines illustrate portions of the balance vehicle that form no part of the claimed design.
